[57] **CLAIM**

The ornamental design for a light attracting insect electrocutor, substantially as shown and described.

DESCRIPTION

FIG. 1 is an isometric view of my light attracting insect electrocutor, looking obliquely at the top and two adjacent sidewalls thereof;

FIG. 2 is an isometric view looking obliquely at the top and the two remaining sidewalls of the trap shown in FIG. 1, the bottom of the trap being plain;

FIG. 3 is an isometric fragmentary view of the wire-type ornamental guard panels mounted in the trap sidewalls as shown in FIGS. 1 and 2;

FIG. 4 is a longitudinal sectional view taken along line 4—4 in FIG. 1 and showing the light source and the electric grid;

FIG. 5 is a transverse sectional view taken along lines 5—5 in FIGS. 1 and 2;

FIG. 6 is a sectional plan view taken along lines 6—6 in FIG. 1.
